(57) **CLAIM**

The ornamental design for a swimsuit, as shown and described.

DESCRIPTION

FIG. 1 is a perspective view of a swimsuit showing my new design;

FIG. 2 is a front elevational view thereof;

FIG. 3 is a rear elevational view thereof;

FIG. 4 is a right side elevational view thereof; and,

FIG. 5 is a left side elevational view thereof.

In the drawings, broken lines having consistent dash length show portions of the swimsuit that form no part of the design to be patented.
